FIG. 2 is a front view thereof.

FIG. 3 is a left side view thereof.

FIG. 4 is a right side view thereof.

FIG. 5 is a top view thereof.

FIG. 6 is a bottom view thereof.

FIG. 7 is a perspective view of a control device showing a
second embodiment of our new design.

FIG. 8 is a front view thereof.

FIG. 9 is a left side view thereof.

FIG. 10 is a right side view thereof.

FIG. 11 is a top view thereof.

FIG. 12 is a bottom view thereof.

FIG. 13 is a perspective view of a control device showing a
third embodiment of our new design.

FIG. 14 is a front view thereof.

FIG. 15 is a left side view thereof,

FIG. 16 is a right side view thereof,

FIG. 17 is a top view thereof.

FIG. 18 is a bottom view thereof.

FIG. 19 is a perspective view of a control device showing a
fourth embodiment of our new design.

FIG. 20 is a front view thereof.

FIG. 21 is a left side view thereof.

FIG. 22 is a right side view thereof.

FIG. 23 is a top view thereof; and,
